L. ROCKE

SEWING MACHINE ATTACHMENT FOR HOOK AND EYE TAPE

Filed July 22, 1922

UNITED STATES PATENT OFFICE.

LOUIS ROCKE, OF BROOKLYN, NEW YORK.

SEWING-MACHINE ATTACHMENT FOR HOOK AND EYE TAPE.

Application filed July 22, 1922. Serial No. 576,664.

To all whom it may concern:

Be it known that I, LOUIS ROCKE, a citizen of the United States, residing at Brooklyn, county of Kings, and State of New York, have invented certain new and useful Improvements in Sewing-Machine Attachments for Hook and Eye Tape, of which the following is a specification.

It is the common and usual practice in the garment industry to attach a hook or eye tape to the edge of a garment to form a binder edge, but with the present methods and apparatus in use for this purpose, from two to three separate operations are necessary to complete the sewing of the tape to the garment, as follows, if the garment is of a certain type an ordinary plain flat binding tape is first sewed upon the garment edge by means of the usual sewing machine binder attachment, after this the hook or eye tape is sewed on. As the presence of the hooks or eyes upon the tape prevents it from passing through the usual binding attachment, it becomes necessary to resort to two separate operations to complete the sewing on of the hook or eye tape, first one edge of the hook or eye tape is sewed to the garment in a single needle machine, so that the edge of the garment extends to the middle line of the tape after which the tape is folded over the edge of the garment to bring the two edges of the tape into alignment and another row of stitching is run thereby completing the operation.

One of the principal objects of this invention is to provide a new and improved method of binding a garment with hook or eye tape, thereby eliminating the repeated handling of and the number of operations heretofore necessary for sewing the tapes to the garments, to avoid the necessity for the use of a preliminary binding tape with the labor and material cost thereof, and to not only eliminate some of the operations commonly used, but to increase the output of the operator while at the same time improving the appearance of the finished garment.

Considered in its more specific aspects, an object of this invention is to provide a new and improved apparatus for sewing on the hook or eye tape binder, which apparatus consists of a new and improved binder, in combination with a special presser foot, both of these parts being especially con-

structed to permit the passage of the hooks or eyes, as well as guiding the material through the sewing machine.

For the accomplishment of these and such further objects as will be apparent to those skilled in the art to which this appertains, the invention consists in the method and the apparatus for carrying out the method herein specifically disclosed in the following specification, it being understood that such changes, variations, modifications and equivalents are comprehended as fall within the scope of the claims hereunto appended.

In the drawings forming a part hereof—

Fig. 1 is a perspective partial view of a sewing machine showing an apparatus embodying my invention attached thereto.

Fig. 2 is a plan view on an enlarged scale of the attachments shown in Fig. 1 with the presser foot shown in dotted lines.

Fig. 3 is a side elevation of the parts shown in Fig. 2, as seen from the right hand side of the sewing machine.

Fig. 4 is a section on the line 4—4 of Fig. 3.

Figs. 5 and 6 are sections on the lines 5—5 and 6—6 of Fig. 2 respectively, and

Fig. 7 is a cross section on the line 7—7 of Fig. 3.

As shown in the drawings on the work table 10 of a common type single needle sewing machine is secured a combined binder and folder attachment which consists of an attaching plate section 12, having the longitudinal slot 12^a therein to receive the attaching screw 12^b adapted to engage a suitable threaded aperture provided in the work table or throat plate of the machine, and a garment guiding plate section 13 between which is located the folding section 14. The folding section 14 consists of a piece of sheet metal having its ends bent over as indicated by the numerals 15 and 16 to form a channel for guiding the tape through the binder, the entrance end lying in a substantially straight vertical plane and curving as indicated at 17 to allow the tape to be fed to the folder from a suitable tape supply such as the reel 18, rotatably mounted to one side and at the rear of the work table. At the inner end of the curved portion 17 the folding section is merged gradually to form a reentrant bend 19, the depth of which increases gradually towards

the delivery end, from which the tape is delivered directly to the presser foot 20 of the machine. The bend 19 also tapers gradually downwardly towards the table at the delivery end according to the well known construction of devices of this character.

The edge of the lower bent portion 15 is beveled off as indicated at 21 to form a wedge portion which engages under the hooks 22 and causes the same to pass along the outer side of the bent portion and thereby permit the hook to swing around to the position shown in Figs. 5 and 6, as the tape is folded. As it is sometimes desirous to vary the line of the meeting edges of the tape as it is sewed to the garment, due to variations in the thickness of the garment material, or in order to have one of the edges of the tape overlap the other, or to vary the amount which the free end of the hook or eye will project beyond the finished garment, means are provided to vary the relative positions of the edges of the channel at the delivery end and such means comprises the metal strip 23 which is suitably secured as by soldering or brazing the same to the upper bent portion 16, adjacent the delivery end thereof. The strip 23 is provided with a longitudinal slot 24 through which the headed adjusting screw 25 passes, the screw 25 being engaged within the threaded hole 26 provided in the attaching plate section 12. The re-entrant portion 19 is cut away as indicated at 27 to permit the upper portion of the folder at the delivery end to be sprung into the desired adjusted position to change the relative positions of the meeting edges of the tape.

The upper part of the re-entrant portion 19 is cut away as indicated by the numeral 28 in Fig. 5, for a short distance inwardly from the delivery end to provide a clearance space for the hook attaching eyelets, while the attaching plate 12 is slotted as at 29 to provide a clearance for the free end of the hooks as they approach the plate 12, due to the downward inclination of the folder towards the delivery end.

It will be noted that the folder extends in a straight line from the curved portion 17 to the delivery end and that the left hand side of the re-entrant bend forms a recessed guide 30 for the edge of the garment, which guide provides a straight guiding surface which ensures the feeding of both the garment and tape to the presser foot and feed of the machine in such a manner that a perfectly even straight stitching of the tape is produced.

The presser foot 20 is cut away as indicated at 31 to provide a clearance space for the passage of the fastening eyelets and also to form a straight edged guide way for the eyelet ends of the tape which provides an additional means for securing the feeding

of the material in a straight line and consequently the production of a straight even stitching.

The inner edge 32 of the garment guiding plate section 13 is cut away at an angle to allow the presser foot and feed to engage the goods as close to the delivery end of the folder as possible and the plate section 13 is offset upwardly as indicated at 33 (Figs. 5 and 6) to permit the reciprocation of the feed. It will be noted that the folding section is cut away as indicated by the numeral 40 in Fig. 3 to form an unobstructed passage way for the hooks, eyes or the like, the lower edge 41 of this cut out portion forming a guide way which engages under the free end of the hooks or eyes and contacts with them adjacent the points at which they are fastened to the tape while the upper edge 42 contacts with the other extremity, of the hooks, eyes or the like.

The operation of the device is as follows, the hook or eye tape is led from the reel 18 and entered into the curved end 17 of the folding section 14, with the free ends of the hooks or eyes pointing downwardly, the beveled edge 21 causing the hooks or eyes to pass along the outer side of the bent over portion 15. As the tape is fed through the folder it will be turned over as indicated in Figs. 5 and 6, and will pass downwardly along the inclined path of the folder from the delivery end of which it will be fed directly to the presser foot.

Due to the downward inclination of the folder, the hooks or eyes will come into sliding contact with the upper face of the plate 12 at a point about under the strip 23, which contact will assist in turning the hooks or eyes into the horizontal position which they finally assume when the tape is stitched to the garment.

As the inclination of the folder is arranged to bring the folded tape down to a point in contact with the table, it becomes necessary to provide the clearance space 29 adjacent the delivery end of the folder to prevent too great a pressure upon the free ends of hooks or eyes which would cause the tape to become wrinkled or creased within the folder. It being necessary in order to keep the tape in a smooth condition to make the channel defined by the bent over portions 15 and 16 barely large enough to allow for the passage of the tape, the clearance space 28 is provided at the delivery end to permit the unobstructed passage for the fastener eyelets as the hooks or eyes are turned up to the horizontal position shown in Fig. 5.

It will be noted from an inspection of Figs. 1 and 7 that the contact of the edge of the cut out portion 31 against the ends of the hooks is such as to exert a pressure towards the right hand side at the rear of the

needle while the pressure of the guide for the garment formed by the re-entrant bend 19 is towards the left and in front of the needle, a two point spaced support is thus 5 formed, which only requires the operator to feed the garment always in contact with the guide portion 30 to ensure an absolutely straight, even stitching, no special attention having to be given to the hook or eye tape.

10 Having thus described my invention, what I claim as new and desire to secure by Letters Patent of the United States, is:—

15 1. In a sewing machine attachment, a combined folder and binder having a folding section consisting of a piece of sheet metal having its edges bent over to form a channel for guiding a tape through the binder, the entrance end of said folding section lying in a substantially straight vertical 20 plane and curved to allow the tape to be fed from a suitable tape supply, the inner end of said curved portion merging into a re-entrant bend increasing gradually toward the delivery end of said folder section, one 25 of said bent over edges being bevelled to form a wedge portion adapted to engage under a hook attached to said tape and cause the same to pass along the outer side of said bent over portion, and permit said hook to 30 swing around into an inclined position as said tape is being folded.

35 2. In a sewing machine attachment as set forth in claim 1, means for varying the relative positions of the bent over edges of the folder section.

40 3. In a sewing machine attachment as set forth in claim 1, means for varying the relative positions of the bent over edges of the folder section, comprising a metal strip secured at one end to the upper bent over portion adjacent the delivery end thereof and provided with means for adjusting the other end of said strip relative to its support.

4. In a sewing machine attachment as set

forth in claim 1, one of said bent over edges 45 of the folder being cut away to permit the upper section of the folder to be sprung into a desired adjusted position relative to the opposite bent over edge.

5. In a sewing machine attachment as set 50 forth in claim 1, the upper part of one of said bent over edges being cut away for a short distance inwardly from the delivery end to provide a clearance space for hook attaching eyelets, said attaching plate being 55 slotted to provide a clearance for the free end of the hooks as they approach said attaching plates due to the downward inclination of the holder towards the delivery end thereof.

6. In combination with a combined binder and folder attachment as set forth in claim 1, a presser foot cut away to provide a clearance space for the passage of hook attaching eyelets and also to form a straight edge 65 guide way for the eyelet ends of fasteners.

7. In a sewing machine attachment as set forth in claim 1, the garment guiding plate section being cut away at an angle to allow a presser foot and feed to engage a 70 tape as close to the delivery end of said guiding plate section, said guiding plate section being offset upwardly to permit the reciprocation of a feed plate.

8. In a sewing machine attachment as set 75 forth in claim 1, the folding section being cut away to form an unobstructed passage way for hooks or eyes, the lower edge of said cut out portion forming a guide way which engages under the free end of the 80 hooks or eyes, and contacts with them adjacent the points at which they are fastened to a tape, while the upper edge of said cut out portion contacts with the other extremity of said hooks or eyes.

In testimony whereof I have affixed my signature.

LOUIS ROCKE.
